(57) **CLAIM**

The ornamental design for a car body, as shown and described.

DESCRIPTION

1. Car body

1.1: Perspective

1.2: Perspective

1.3: Front

1.4: Back

1.5: Left

1.6: Right

1.7: Top

The bottom view of the design is omitted since it is not easy to see or cannot be seen during usage.

The portions of the car body shown in a de-emphasized and half-tone form surrounded by broken lines and the broken lines representing a boundary are for environmental and illustrative purposes and form no part of the claimed design.
